UNITED STATES PATENT OFFICE

132,206

DESIGN FOR A DOLL GROUP

Dora Mohr, Boston, Mass.

Application September 3, 1941, Serial No. 103,143

Term of patent 7 years

To all whom it may concern:

Be it known that I, Dora Mohr, a national of the German Reich, and a resident of Boston, in the county of Suffolk, Commonwealth of Massachusetts, have invented a new, original, and ornamental Design for a Doll Group, of which the following is a specification, reference being had to the accompanying drawings, forming part thereof.

In the drawings:

Fig. 1 is a perspective view of a doll group from the front, showing my new design; and

Fig. 2 is a perspective view of the doll group from the rear.

I claim:

The ornamental design for a doll group, substantially as shown.

DORA MOHR.
